UNITED STATES PATENT OFFICE.

DE LASKI T. CLEMONS, OF HORNELLSVILLE, NEW YORK.

DOUBLE-BELT SANDER.

No. 818,518.

Specification of Letters Patent.

Patented April 24, 1906.

Application filed November 16, 1904. Serial No. 232,983.

To all whom it may concern:

Be it known that I, DE LASKI T. CLEMONS, a citizen of the United States, residing at Hornellsville, in the county of Steuben and

5 State of New York, have invented certain new and useful Improvements in Double-Belt Sanders, of which the following is a specification, reference being had therein to the accompanying drawings.

10 The present invention relates to belt-sanding machines of that type in which an endless sand-belt is given a rapid continuous movement over the work to dress and finish the same, suitable belt-guide and pressure appliances being provided to bring the belt into contact with the work.

The machine which I have invented comprises as one of its essential features improved means and devices for bringing the sand belt 20 or belts into contact with the work, so as to maintain either a uniform pressure of the sand-belt upon the work to be finished or to vary the pressure along the belt at the will of the operator in order that any "low" places 25 in the work may be effectively reached by the belt and properly finished, the said pressure devices being operated by fluid-pressure to the end that effective and uniform pressure of the belt upon the work may be secured and that a satisfactory variation in 30 pressure along the belt may be quickly and conveniently effected.

Another feature of the machine hereinafter described is the means for supporting and adjusting the work-support relative to the sand-belts and preserving the relative positions of the table, belts, and pressure mechanisms.

Other features of novel construction will be hereinafter pointed out, and those features 40 which I deem as peculiarly of my invention will be defined in the claims appended hereunto.

While I shall describe hereinafter and have illustrated in the drawings herewith, a double-belt sander, it will be apparent that the invention is equally applicable in many respects to a sander having a single belt, and such use and application of the novel features of construction are to be understood as 45 within the range of my invention.

Referring to the drawings accompanying and forming a part of this specification, Figure 1 is a plan view of the machine, the upper runs of the sand-belts being broken away to 55 show the pressure mechanism, which is located between the upper and lower runs

thereof. Fig. 2 is a view in side elevation of the machine, parts of the supporting-frame being broken away or in section to illustrate the supports and adjusting mechanism for 60 both the work-table and the pressure devices. Fig. 3 is a detail plan view approximately upon the line 3 3 of Fig. 2 looking in the direction of the arrows to illustrate the work-table supports and the adjusting devices therefor. 65 Fig. 4 is an enlarged detail view of a portion of the work-table-supporting tracks, the work-table, the pressure mechanism, and their several adjusting devices. Fig. 5 is an enlarged sectional view transversely of the 70 belt-guides and the pressure devices to illustrate the fluid-pressure connections for said pressure devices. Fig. 6 is a detail view to illustrate the manner of supporting the belt-guide. Fig. 7 is a detail bottom view of the 75 three-way cock for controlling the fluid-pressure and the pressure connections therewith. Fig. 8 is a detail sectional view of the operating mechanism for raising and lowering the pressure mechanism to secure an adjustment 80 of the same relative to the work and work-table.

Referring to the drawings by numerals, like numbers indicating like parts in the several views, 2 indicates the base of the machine, which may be of any suitable or desired construction and which has at each end a hollow post or pedestal 3, which form the supports for the work-table, pressure mechanism, sand-belt pulleys, and driving shafts 90 and pulleys of the machine, said posts being slotted or open on their inner sides to permit of the vertical movement and adjustment of some of the parts which are housed within them, as will hereinafter appear. Mounted in 95 suitable bearings at one end of the machine is the main driving-shaft 4, which is provided at one end with the usual fast and loose driving-pulleys, which receive power from any suitable prime motor. Mounted upon said shaft 100 4 are the sand-belt pulleys 5 and 6, which drive the sand-belts 7 and 8, one of which is intended to be a coarse-sand belt for dressing the rough work, while the other belt is a fine-sand belt for finishing the surface of the 105 dressed work.

At the other end of the machine are mounted corresponding belt-pulleys carried by stub-shafts 9, fixed or formed integral with transversely-placed plates 10, which in turn are 110 pivotally mounted upon longitudinally-sliding plates 11, mounted in a dovetailed bed-

plate 12, extending outwardly from the end of the machine-frame. Each of these sliding plates 11 is provided with an adjusting-screw 13, so that the said sliding plates 11, the plates 5 10, and the sand-belt pulleys 7 and 8 carried thereby may be independently adjusted to secure the proper tension on the sand-belts. The said pivoted plates 10 may be angularly adjusted, by means of independent screws 14, 10 in order that the belt-pulleys may be trued or alined, lock-screws 15 passing through arc-shaped slots 151 in said plates 10 to lock the plates in their adjusted positions.

Extending longitudinally of the machine 15 at the rear thereof is a supporting-beam 16, on which beam in suitable bearing-lugs 161 is mounted a rocking shaft 17, said shaft having fixed thereto supporting-arms 18, from the forward end of which arms 18 the pressure mechanism is hung. As above stated, 20 this pressure mechanism, which forms an important part of my invention, will be described and illustrated in connection with a double-belt sander, although it will be distinctly understood that this feature of my invention, as well as the other novel features, 25 are equally applicable to a single-belt sander.

Hung from the ends of the supporting-levers 18 are toggle-frames which form the 30 immediate supports for the belt-guides and pressure devices, said toggle-frames comprising two horizontal members 19, pivotally mounted upon hangers 20, which hangers are pivotally connected at their upper ends to the 35 ends of the levers 18. The outer ends of the horizontal members 19 of the toggle-frames are connected by means of vertical members or links 21, as clearly shown in Fig. 4. It will be obvious that the said toggle-frame described may be thrown from the usual position (shown in full lines in Fig. 4) to the distorted position (shown in dotted lines therein) to bring one or the other of the belt-guides and pressure devices carried by said toggle-frame down upon the work. To the lower 40 ends of the said vertical toggle members 21 are secured supporting-plates 22, said plates being provided with a series of pressure-cylinders 23, arranged in pairs crosswise of the plate 22. Within these pressure-cylinders 23 are mounted pressure-pins 24, the lower ends of which project through suitable yokes 25 on the under side of the plate 22, lock-nuts 26 being provided to limit the downward 45 movement of said pressure-pins. (See Fig. 5.) Carried by said pressure-pins 24 are the belt-guides or pressure-plates 27, which bear upon the under runs of the sand-belts 7 and 8, said pressure-plates 27 being preferably made of thin sheet-steel of the proper width to suit the width of belt and of such gage as to give the necessary degree of flexibility. In order to provide a smooth yielding surface for the under side of the said guide 55 27, it will preferably be covered with felt

and have an outer covering of paper or other smooth friction-reducing material, as is customary in sand-belt guides. The said belt-guides 27 may be supported from the lower ends of the pins in any suitable manner, and I find that a good construction and one which gives a proper support for the belt-guide without impairing its flexibility is that shown in the drawings, in which the end pairs and, if desired, several intermediate pairs of pressure-pins 24 are provided with supporting lugs or projections 28, which engage a bracket 29 on the upper side of the belt-guide 27, as clearly shown in Fig. 6, the said lug 28 moving freely through the hole in the bracket 80 29, so as to permit flexing of the belt-guide 27 without straining the supporting connections. The means for supplying fluid-pressure to the said pressure-cylinders 23 and actuating the pressure-pins 24 comprises two 85 fluid-pressure pipes 30, which may be mounted in convenient relation to the pressure-cylinders and in the present construction are shown as mounted on the lower horizontal members 19 of the toggle-frame. (See Figs. 90 1, 2, and 4.) The said pipes 30 are connected, respectively, by suitable supply-pipes 31 with two pressure-tanks 32, one of which is a high-pressure tank and the other a low-pressure tank, said tanks being kept under pressure 95 from any suitable air-compressing device which may be driven from the driving-shaft 4 of the sander or by an independent motor, as may be desired.

Connected across the pipes 30 at suitable 100 intervals are a series of three-way cocks 33, from which cocks suitable connections 34 with the pressure-cylinders 23 are made. These connections 34 (see Fig. 5) are shown in the present instance as flexible tubing in order to 105 permit movement of the supporting-plates 22 and the pressure devices carried thereby without interfering with the pressure connections when the toggle-frame is rocked to lower one or the other of the belt-guides 27. 110 I have shown four pressure connections or leads 34 from each three-way cock 33, so that four pressure-pins 24 (two for each sand-belt) are controlled by each cock 33; but it will be understood that this arrangement may be 115 varied as may be found desirable and a greater or less number of pressure-pins 24 controlled by each cock 33. It will be seen that with this construction the pressure may be thrown from one sand-belt to the other, 120 as desired. It may be uniformly supplied to all of the pressure-pins of either one of said belts. It may be varied lengthwise of a belt by throwing the high pressure on one group of pins and the low pressure on another group, and it may be cut off altogether and the pressure-pins rendered inactive at the will of the operator, for since there is a controlling-cock for each pair of pressure-pins on the respective sand-belts the pressure 125 130

of the successive pairs of pins may be readily varied, so that if it be desired to finish a low spot at any point in the work the operator may do this by throwing on the high pressure at that particular point, leaving the rest of the pressure-pins under low pressure, if desired.

In order that the pressure mechanism just described may be normally held in an elevated position, a counterweight 35 is provided, said counterweight being adjustably mounted on an arm 36, secured to the shaft 17, on which the arms 18, which carry the pressure mechanism, are mounted. (See Figs. 1 and 4.)

In order that the operator may raise and lower the pressure mechanism above described relative to the work-support and work, there are provided two arms or levers 37, which are pivoted on a shaft 38, carried by the longitudinal beam 16, (see Fig. 4,) the said arms 37 being connected at their forward ends to the hangers 20 of the toggle-frames. The said shaft 38 has its ends extended, as shown in dotted lines, Fig. 2, and at each end of said shaft 38 is a forwardly-projecting arm 40, from which a pull-rod 41 depends, said pull-rod 41 being threaded in a sleeve 42, carried by a bracket 43, said bracket having on its inner side a roller 44, as clearly shown in Figs. 2, 3, 4, and 8. The said sleeve 42 passes through a sprocket-wheel 45, carried by a bracket 46, secured to the tracks 61, said sleeve and sprocket being splined together, so that the sleeve may slide freely through the sprocket and its supporting-bracket, while at the same time rotation of the said sprocket 45 will rotate the sleeve 42 and run said sleeve up or down on the pull-rod, according to the direction of movement of the sprocket. The said rollers 44 project inwardly beneath vertically-movable bars 48, which are hung by means of links 49 beneath the work-table 50, the said links 49 being preferably fixed to the ends of the cross-shafts 51, mounted in depending lugs 52 on the under side of the table 50. At both ends of the table 50 one of the shafts 51 is provided with forwardly-projecting upwardly-curved arms 54, which are connected by a handle-bar 55, extending across the front of the machine, by means of which the operator may raise and lower the said bars 48 through the link connections just described. This movement of the bars 48 when the operator forces them downwardly against the rollers 44 will move the sleeves 42 downwardly and through the pull-rods 41 exert a downward pull on the arms 40, and in turn through the rocking shaft 38 and the arms 37 the toggle-frame and pressure mechanism will be forced downwardly against the action of the counterbalancing-weight into contact with the work.

In order that one or the other of the sand-

belts may be brought into operation either for dressing the work with the coarse belt or for finishing it with the fine belt, the toggle-frames are connected by means of a rocking shaft 56, preferably secured to the central hangers 20 of the toggle-frames, so that when the said shaft 56 is rocked the toggle-frames will be thrown from the normal parallel positions (shown in full lines in Fig. 4) to the distorted oblique position (shown in dotted lines in Fig. 4) or to the opposite oblique position, as the case may be, in order to bring one or the other of said belt-guides or belts against the work.

It will be seen that the angular relation of the belts to the work does not change, but that the belts are merely shifted to different planes in moving to or from operative position. Furthermore, it will be observed that movement of one belt causes a corresponding movement of the other belt in the opposite direction.

To provide convenient mechanism within the reach of the operator for rocking the said shaft 56, I mount a pinion 57 on a suitable support about midway of the machine, which pinion 57 meshes with a pinion 58 on the said rock-shaft 56, an operating-handle 59 being provided to rotate said pinion 57 from one position to another, said operating-arm preferably resting upon a guide-plate 60, having suitable stops at each end to limit the movements of the said handle.

The work-table 50 rests upon tracks 61, said work-table having the usual grooved supporting-rollers 62, and in order that the said tracks 61 and work-table 50 may be raised or lowered to accommodate different thicknesses of work the said tracks 61 are supported by means of brackets 63, carrying sprocket-wheels 64, which are threaded on and supported by screw-threaded rods or posts located within the end posts or supports 3 of the machine-frame. (See Figs. 2 and 3.) The said sprocket-wheels 64 are engaged by an endless sprocket-chain 65, which at the front of the machine engages a hand-operated sprocket-wheel 66, having a crank 67, by means of which the operator may rotate the same and move the chain 65, and at the rear end of the machine is preferably placed a tightening roller or sprocket 68. It will be seen that by this construction the tracks 61, the work-table 50, and their associated parts may be raised or lowered as the sprocket-wheels 64 are rotated in one direction or the other by the chain 65, and the adjustments of the table necessary to accommodate different thicknesses of work may thus be secured.

In order to maintain the same relative positions between the table and the pressure mechanisms when the table is adjusted to accommodate different thicknesses of work and to provide for simultaneous adjustment of

the work-table and pressure mechanism, the said sprocket-chain 65 engages the sprocket-wheels 45 on the sleeves 42 at each end of the machine, which are threaded to the pull-rods 5 41, and as the chain 65 is moved in one direction or the other rotation of the sprocket-wheels 45 will actuate the sleeves 42 and raise or lower the sleeve and sprocket on the pull-rods 41, thus keeping the parts always 10 in proper relation to each other and giving simultaneous adjustment to them.

From the foregoing it will be seen that I have provided a sanding-machine in which the work may be rough-dressed by the coarse belt and then finished by the fine belt without removing it from the work-table, that provision is made for obtaining an absolutely uniform pressure upon the sand-belts throughout their length when desired, while 15 20 at the same time the operator may at will vary this pressure at different points lengthwise of the work, and that either belt may be put under high or low pressure, as may be found necessary. Again, the coarse or fine 25 30 belts and their respective pressure mechanisms may be readily and quickly shifted to bring the one or the other into operative relation to the work. Furthermore, convenient means for adjusting the work-table and pressure mechanism to accommodate different 35 40 thicknesses of work are provided, all within easy access to the operator.

While I have shown and described a particular construction, it will be apparent that 35 the same may be varied to a considerable extent without departing from the spirit of my invention, and I do not, therefore, limit myself to any of the details of construction shown and described except so far as I am 40 limited by the terms of the appended claims.

I have shown, described, and claimed a "sanding-belt," but it must be understood that this term is not to be construed as limiting my invention to a machine in which a 45 sanding-belt only is used, for it is apparent that finishing-belts other than sanding-belts may be employed without any change in the construction or operation of this machine. Such interchanging and substitution of belts 50 55 in a finishing-machine of the type shown and described is a matter governed solely by the need of the work in hand, and since it is a thing within the discretion of the workman and not dependent on machine design all such belt changes are within the purview of my invention.

Having described my invention, I claim—

1. In a sanding-machine, the combination with a suitable work-support, of a traveling 60 sand-belt, a pressure device to hold the belt to the work, a source of fluid-pressure, connections between said pressure device and the source of pressure, and means for controlling said pressure connections.

65 2. In a sanding-machine, the combination

with a suitable work-support, of a traveling sand-belt, a flexible belt-guide, and pressure devices operated by fluid-pressure to hold said belt-guide and belt against the work.

3. In a sanding-machine, the combination 70 with a suitable work-support, of a traveling sand-belt, a flexible belt-guide, and a series of fluid-pressure-operated pins to hold said belt-guide and belt against the work.

4. In a sanding-machine, the combination 75 with a suitable work-support, of a traveling sand-belt, a flexible belt-guide, and fluid-pressure-operated pins by which said belt-guide is supported and the said guide and belt held against the work.

80 5. In a sanding-machine, the combination with a suitable work-support, of a traveling sand-belt, fluid-pressure-operated means to hold said belt against the work, a high-pressure pipe, a low-pressure pipe, and means 85 for connecting said fluid-pressure-operated means with either of said pipes.

6. In a sanding-machine, the combination with a suitable work-support, of a traveling sand-belt, a plurality of fluid-pressure-operated devices to force said belt against the work, a high-pressure pipe, a low-pressure pipe, and means for connecting said pressure devices with either one or both of said pipes.

90 7. In a sanding-machine, the combination 95 with a suitable work-support, of two traveling sand-belts running in fixed angular relation to the work, a pressure device for each of said belts, and means for moving either one of said belts toward or from the work without changing its angular relation thereto.

8. In a sanding-machine, the combination with a suitable work-support, of two traveling sand-belts movable toward or from the work, and connections between said belts 105 whereby movement of either belt will cause movement of the other in an opposite direction.

9. In a sanding-machine, the combination 110 with a suitable work-support, of two traveling sand-belts, belt-guides for each of said belts, a toggle-frame supporting said belt-guides, and means for rocking said toggle-frame to throw one or the other of said guides against its belt and hold said belt against the 115 work.

10. In a sanding-machine, the combination with a suitable work-support, of two traveling sand-belts, belt-guides for each of said belts, a pressure device for each of said belt-guides, a toggle-frame supporting said belt-guides and pressure devices, and means for 120 rocking said toggle-frame to throw one or the other of said guides and pressure devices against its belt and hold said belt against the 125 work.

11. In a sanding-machine, the combination with a suitable work-support, of two traveling sand-belts, a belt-guide for each of said belts, a normally elevated supporting-frame 130

5 said guides, manually-controlled means for depressing said supporting-frame, and means for throwing one or the other of said guides against its belt and hold said belt against the work.

12. In a sanding-machine, the combination with a suitable work-support, of two traveling sand-belts, a belt-guide for each of said belts, a pressure device for each of said guides, a normally elevated supporting-frame for said guides, manually-controlled means for depressing said supporting-frame, and means for throwing one or the other of said guides and pressure devices against its belt and hold said belt against the work.

13. In a sanding-machine, the combination with a suitable work-support, of two traveling sand-belts, a belt-guide for each of said belts, a toggle-frame to support said guides, counterweighted supporting-arms normally holding said frame and guides in elevated position, manually-controlled means for depressing said frame and guides, and manually-operated means for throwing said toggle-frame to an oblique position to bring one or the other of said belt-guides and belts into operative relation to the work.

14. In a sanding-machine, the combination with a suitable work-support, of a traveling sand-belt, a belt-guide, groups of fluid-pressure pins arranged lengthwise of the belt-guide, a source of pressure, and independent controlling-cocks for each group of pressure-pins.

15. In a sanding-machine, the combination with a suitable work-support, of a traveling sand-belt, a belt-guide, groups of fluid-pressure pins arranged lengthwise of the belt-guides, a high-pressure supply, a low-pressure supply, and independent cocks for each group of pins controlling both the high-pressure and low-pressure supply.

16. In a sanding-machine, the combination with a suitable work-support, of two traveling sand-belts, belt-guides for each of said belts, groups of fluid-pressure pins arranged lengthwise of the belt-guides, a source of fluid-pressure, and a single cock for one or more of the groups of pressure-pins for each belt-guide.

17. In a sanding-machine, the combination with a suitable work-support and two traveling sand-belts, pressure mechanism comprising movable frames, supporting-plates carried by said frames, fluid-pressure cylinders on said plates, pressure-pins in said cylinders, belt-guides hung from said pins, and means for rocking said frames to bring one or the other of said belt-guides into operative relation to its belt and the work.

18. In a sanding-machine, the combination with a suitable work-support and two traveling sand-belts, of pressure mechanism comprising movable frames, supporting-plates carried by said frames, fluid-pressure cylinders on said plates, pressure-pins in said cylinders,

ders, belt-guides hung from said pins, a rock-shaft carried by said frames, and manually-operated means for rocking said shaft and frames to bring one or the other of said belt-guides into operative relation to its belt and the work.

19. In a sanding-machine, the combination with suitable sanding instrumentalities, of a vertically-adjustable work-support, vertically-adjustable pressure mechanism to hold said sanding instrumentalities against the work, and means for simultaneously adjusting said work-support and pressure mechanism to accommodate different thicknesses of work.

20. In a sanding-machine, the combination with suitable sanding instrumentalities, of a work-support, supporting-posts for said work-support, means for adjusting said work-support vertically on its posts, pressure mechanism to hold said sanding instrumentalities against the work, and means for adjusting said pressure mechanism vertically simultaneously with the adjustment of the work-support.

21. In a sanding-machine, the combination with a traveling sand-belt, of a work-support, supporting-brackets thereon, screw-threaded posts engaged by said brackets, sprocket-wheels carried by said brackets and threaded on said posts, pressure mechanism to hold the belt against the work, pull-rods connected with said pressure mechanism to raise and lower the same, brackets on the work-support through which said pull-rods 100 pass, sprocket-wheels carried by said brackets, and a drive-chain engaging the work-support and pressure mechanism sprocket-wheels to give a simultaneous adjustment thereto.

22. In a sanding-machine, the combination with suitable sanding instrumentalities, of a work-table, counterbalanced pressure mechanism above said table, pull-rods connected with said pressure mechanism, and vertically-movable bars carried by said table and engaging said pull-rods to move said counterbalanced pressure mechanism into operative relation to the work-table and work.

23. In a sanding-machine, the combination with suitable sanding instrumentalities, of a work-table, counterbalanced pressure mechanism above said table, pull-rods connected with said pressure mechanism, brackets on said pull-rods, rollers mounted on said brackets and extending beneath said table, and vertically-movable bars on said table engaging the rollers on said pull-rod brackets to move the pressure mechanism into operative relation to the work-table and work.

24. In a sanding-machine, the combination with suitable sanding instrumentalities, of vertically-movable supporting-tracks, of a work-table mounted on said tracks, counterbalanced pressure mechanism above said ta-

ble, pull-rods extending downwardly from said pressure mechanism, brackets on said tracks through which said pull-rods pass, sleeves threaded on said pull-rods and vertically movable in said brackets, sprocket-wheels carried by said brackets and splined to said sleeve, brackets carried by said sleeves, rollers on said brackets, and vertically-movable bars hung from said work-ta-

ble and engaging said rollers to move said pressure mechanism into operative relation to the work-table and work.

In testimony whereof I affix my signature in presence of two witnesses.

DE LASKI T. CLEMONS.
